UNITED STATES PATENT OFFICE

ANDREW SMITH, OF SAN MATEO, CALIFORNIA, ASSIGNOR TO SMITH METAL PERFORATING COMPANY, OF SAN MATEO, CALIFORNIA.

SHEET-METAL CASING FOR DRAINAGE CULVERTS, CONDUITS, SCREENS, WELLS, &c.

1,055,674.

Specification of Letters Patent. Patented Mar. 11, 1913.

Application filed March 16, 1912. Serial No. 684,177.

To all whom it may concern:

Be it known that I, ANDREW SMITH, a citizen of the United States, residing at San Mateo, in the county of San Mateo and State 5 of California, have invented certain new and useful Improvements in Sheet-Metal Casings for Drainage Culverts, Conduits, Screens, Wells, &c., of which the following is a specification.

10 This invention relates to metal casings for the linings of water and oil wells and which may also be used for drain tiles, culverts, and irrigating tiles or conduits for sub-irrigation.

15 My present invention relates particularly to corrugated casings for the above mentioned purposes.

Corrugated metal casings are especially adapted for well-strainers or casings, which 20 are frequently required to be carried down to a depth of several thousand feet, and are subjected to very great pressures by reason of its rigidity and strength for the weight of metal used. It is also adapted for drain tiles 25 and culverts which are liable to be subjected to heavy weights and pressures, especially when they underlie road-crossings and railways. It is customary to join the ends of the sections of the casing by means of rings or 30 bands riveted thereto, or by means of other special connecting members, so that the casing may be lowered section by section into the well and constitute a continuous metal lining.

35 One of the objects of my present invention is to provide a sectional metal casing in which the sections or units can be directly connected or united to each other, without the necessity of using auxiliary connecting 40 members. The advantages arising from my improvements are important in this art aside from the benefits to be derived from the elimination of the auxiliary connecting members. The sections may be more quickly 45 joined, and the completed casing is more symmetrical and uniform in external configuration, offering less obstruction as it is fed into the bore of the well.

Another object of my invention is to provide 50 a duplex or double-walled casing in which the inner and outer casing walls shall coöperate to produce an exceedingly strong

and rigid structure and at the same time may serve as an efficient strainer when perforated to permit the passage of water or oil. 55 When the casing of a well-strainer or drain-tile passes through sand stratum, it is essential that the very fine particles which pass through the perforations in the outer casing wall shall be conducted through the inner 60 casing wall and not be permitted to lodge between the walls or clog the apertures, and my invention especially provides for these conditions. I so arrange the structure that the parts of the inner and outer casings containing the perforations shall be spaced from each other and that the intermediate parts shall form strengthening ribs and mutually brace each other.

Under many conditions in well work, 70 drainage, and irrigation, it is desirable that the units or sections shall be uniform and interchangeable, the opposite ends being of different diameters so that the larger end of any section shall connect with the smaller 75 end of the adjacent section. My invention enables the sections to be thus coupled and to be telescoped to a greater or less extent, so that the casing may be substantially single walled or double walled according to 80 the conditions which are necessary in any case.

In addition to the purposes previously specified, it is obvious that the casing disclosed herein may be used as a conduit for 85 various purposes, for instance as a conveyer for solid, liquid, or gaseous substances; thus it may be used as a stack to convey the smoke and gases from manufacturing plants.

Other objects will appear from the following description, in connection with the accompanying drawings, in which—

Figures 1 to 7, inclusive, and 10 to 14, inclusive, are elevations, partly in section, of different forms of casings embodying my invention; Figs. 8 and 9 are cross-sections of casing sections showing different ways of forming the perforations in the casing.

In my present invention, each section or unit is provided with spiral corrugations, 100 which serve not only to greatly enhance the strength and rigidity of the casing, but constitute the sole means of connecting the units or sections into a continuous casing.

When the casing serves as a drainage conduit or a well-strainer or curbing, the walls are perforated, preferably in the manner disclosed in my copending application, Serial Number 489,642, filed April 13, 1909.

In Fig. 1, I have shown an embodiment of my invention in which the duplex casing is formed of spirally corrugated outer sections 2, and inner sections or units 3, the corrugations of the inner sections being screwed into those of the outer sections and these being arranged to break joints so as to form a complete double-walled casing. In order that there may be no danger of the perforations 4, 5, in the outer and inner sections being closed, since it frequently happens that they will not be opposite, I provide a space 6 between the walls of the casing by making the recessed portions 8 between the corrugations of the outer tube shallower than the corresponding portions 9 of the inner tube. Any sand or particles which pass through the outer perforations or slots, will pass into the space 6 and thence through the inner 25 perforations. To insure the passage of the sand from the spaces 6, the inner slots 5 are preferably larger than the outer slots 4.

In case it is desired to provide an exceedingly rigid casing for a well or conduit without the drainage function, the sections may be formed, as in Fig. 2, in which the inner sections 3^a and outer sections 2 fit snugly throughout their extent.

Under some conditions, as when it is desirable to cement the space between the outer casing and the well bore, or when it is desired to leave drainage channels between the outer and inner casing sections, I provide a duplex casing with imperforate inner sections 10, and perforated outer sections 2, as shown in Fig. 3. In this arrangement, I have shown the inner sections formed of similar convex and concave portions, the latter co-operating with the outer walls to 45 form continuous channels 6^a extending spirally around the casing.

When the perforations are not needed, both the inner section 10 and the outer section 2^a are preferably formed of regular 50 corrugations, the inner and outer sections fitting closely throughout their extent, as shown in Fig. 4. In some forms of well drilling it is necessary to rotate the casing in the construction of the well, and for this 55 purpose the casing units or sections may be provided with lugs to engage the rotary driving mechanism. I have shown, for purposes of illustration, in Fig. 4, at 7, the manner in which these lugs may be formed 60 extending across the concavities of the casing. It will be understood that these lugs will be placed along the casing at such intervals as may be necessary to provide a sufficient number of engagements with the 65 rotary driving mechanism.

Instead of constructing the perforated portions of straight annuli, as in Fig. 1, both inner and outer sections may consist of alternate convex and concave portions, the concavities of the outer section being shallower than those of the inner section to provide spiral channels or spaces 6^b between the sections of the casing, as shown in Fig. 5. Another important advantage of making the concave portions of the casing shallower or of less curvature than the convex portions, resides in the greater stiffness which is thereby imparted to the pipe to resist longitudinal stresses.

In each of the forms previously described, the spiral ribs or corrugations have projected outwardly. Under some conditions it is desirable to have the outer surface of the casing as smooth and regular as possible, while still preserving the rigidity of the corrugated tube. With this end in view, I construct the units or sections in the manner shown in Fig. 6, in which the spiral corrugations project inwardly, leaving spiral grooves 12 in the exterior walls, alternating with straight spiral portions 14.

In Fig. 7, I have shown a construction similar to Fig. 6, in which both inner and outer sections are perforated for drainage purposes, and the parts are constructed to form a channel or space 6^c between the perforated portions for the purpose previously described. When the slots in the inner and outer sections of the casing are opposite each other, it may happen that, if the casing were subjected to great pressures, the slots might be distorted or even closed. By arranging the slots in the inner and outer sections at an angle to each other, as illustrated in Fig. 7, the perforated portions will reinforce each other in case of great pressures exerted thereon, and the casing perforations will always insure a passage from the outer wall through the inner wall of the casing, so that the drainage will be maintained.

In Figs. 8 and 9, I have shown two different forms of slotted casings which may be employed, which I have previously disclosed in my applications, Serial Numbers 489,642 filed April 13, 1909, and 630,886 filed June 2, 1911, Patent No. 1,028,066, dated May 28, 1912. In the form shown in Fig. 8, the metal is preferably sheared while in the sheet or plate, to form a plurality of slits, and the metal upon opposite sides of each slit is forced in opposite directions, thereby forming perforations or slots between the adjacent edges of the projections. The resulting plate is then formed into a tubular casing, as shown in Fig. 8, the meeting edges being united either by welding electrically, or by the oxyacetylene method or in any other manner of forming a joint or seam that may be desired, so that the casing becomes an integral unit. In said

application No. 630,886, I have described a method of forming a casing with V-shaped slots, such as illustrated in Fig. 9.

In all of the forms heretofore described, the inner section of the casing is of smaller diameter, so that it may be screwed into the corrugations of the outer section. It is also desirable to use sections which are of uniform size, and which constitute both the inner and outer walls of the duplex casing. For this purpose, I have shown in Fig. 10 a section or casing unit, each half of which is of a different diameter so that the smaller end of one section will screw into the larger end of the adjacent section. In this manner the casing may be built up or extended to any desired length and forms a continuous unbroken double-walled conduit or drain. In order that the different diameters of the opposite halves may be more apparent, I have shown the outer broken construction lines and have indicated in dotted lines an adjacent section over the smaller top half. This form of casing unit possesses many advantages for drainage and well casings. In deep wells, where great pressures are encountered, it is to be used as a duplex or double-walled casing, but in shallow wells and in drainage work, where it is only necessary to employ a single thickness, the units are merely screwed a short length into each other sufficient to form a joint or connection.

In Fig. 11, I have shown another form, in which each section or unit tapers from one end to the other, and the smaller end of each section being adapted to telescopically screw into the larger end of the adjacent section by means of the spiral corrugations. It is obvious that when screwing one section into another, the first few turns will fit loosely, and will gradually become tighter until the inner unit or section has reached substantially the center of the coöperating telescoping section, when the corrugations threading upon each other will fit tightly. Each section, therefore, becomes an outside member for half its length and an inside member for the other half in the united casing.

In Fig. 12, I have shown a casing formed of inner sections which taper from the center in both directions, and other sections which flare outwardly from the center in both directions. In connecting these units together, the inner and outer sections fit loosely and screw together very easily for a few turns, but may be made to fit or wedge very tightly when the parts are completely telescoped. This construction forms an exceedingly strong and rigid casing, capable of resisting enormous pressures.

When the casing is used as a drainage tile or irrigating pipe, any of the forms previously described may be employed, but the form shown in Fig. 10, having opposite

ends of different diameters, is peculiarly adapted for this purpose because a single-walled casing may be constructed. In some cases it is desirable to perforate only one side or longitudinal half of the units as illustrated in Fig. 13. When the sections are connected to form the drainage tile, the perforations are arranged uppermost, so that the imperforate lower side may serve as a conduit to convey the water entering the perforations of the drainage casing or to be discharged outwardly through the perforations when the tile is used as a sub-irrigation pipe. As previously pointed out, in using this form of unit, adjacent sections or units are connected by screwing the corrugations together for perhaps a couple of turns, thus making a continuous single-walled casing.

Instead of forming curved corrugations in the walls of the units, I may employ the angular or zigzag form shown in Fig. 14.

The important advantages of my present invention in the art of well casings, drainage and irrigation tile, etc., will now be apparent to irrigation engineers and others skilled in these matters. The spiral corrugations not only constitute strengthening ribs, adding rigidity to the casing and forming overhanging abutments projecting beyond and protecting the perforated portions, but provide a very superior means of connecting the sections or units into a continuous casing of any desired length. By this construction, I not only avoid the use of auxiliary connecting rings, but eliminate the danger of imperfect joints by reason of the stripping of the rivets in such connecting rings. The work of connecting the sections is very materially lessened, since it is merely necessary to screw one unit into the next in order to securely unite the sections, and no riveting is required. Moreover the completed casing presents a uniform exterior configuration, which is more easily inserted into the bore of the well. Furthermore, when the double casing is employed, such as shown in Figs. 1, 3, 5, 7 and 10, a continuous spiral channel is formed between the inner and outer walls of the casing which greatly enhances the efficiency for drainage purposes. In the form shown in Fig. 3, when the bore of the well is cemented to shut off surface drainage into the well, the spiral channel between the inner and outer casing walls facilitates the cementing process by allowing the cement which is forced up between the well bore and the casing, to enter the channel when obstructions are met, and to pass out again into the space between the well-bore and the outer pipe. This insures a perfect seal between the well-bore and the casing. This process of cementing and sealing the casings in the wells to shut off surface drainage is

covered in my copending application, Serial Number 685,665, filed March 23, 1912.

While I have described in detail the constructions illustrated in the accompanying drawings for the purpose of disclosing a number of embodiments of my invention, it is evident that changes may be made therein without departing from the spirit of my invention, and it is my purpose to cover all such changes and modifications in my claims. It will be obvious to engineers that any of the forms of corrugated sections disclosed in the drawings may be perforated and used for drainage purposes, and also that any of said forms may be imperforate and may be used for casings, conduits, stacks, and for other purposes.

I claim:

1. A casing for wells or drainage purposes, comprising a tubular metal member having spiral corrugations extending longitudinally thereof, and perforations intermediate adjacent convolutions of said corrugations, the intermediate portions between the corrugations being of less curvature than the corrugated portions.

2. A sheet metal casing for wells, conduits, or drainage purposes, comprising a tubular member having spiral corrugations extending continuously throughout the length thereof, said member having the opposite longitudinal halves of different diameters, whereby it is adapted to telescope an adjacent member by screwing the corrugations of one member into those of the other member.

3. A sheet metal casing for wells, conduits, or drainage purposes, comprising a tubular member having spiral corrugations extending longitudinally thereof, said member being adapted to telescope an adjacent member by screwing the corrugations of one member into those of the other member, and having lugs upon the outer wall extending between adjacent convex portions to provide means for rotating the same.

4. A sheet metal drainage casing section provided with spiral corrugations extending continuously throughout the length thereof and with draining apertures in the concave portions, the walls of each longitudinal half of said section tapering regularly throughout its extent.

5. A sheet metal drainage casing section provided with spiral corrugations extending continuously throughout the length thereof, said casing section having opposite longitudinal halves of different diameters, the diameter of one half being greater throughout its extent than the diameter of the other half, whereby a plurality of like sections may be connected into an extended casing of any desired length.

6. A duplex casing for wells, conduits, or drainage purposes, comprising telescoping

sections, each section having spiral corrugations extending longitudinally and adapted to engage the corrugations of the telescoping section, the intermediate portions between the corrugations of the outer section being spaced from the corresponding part of the inner section, whereby a spirally extending cavity or space is provided between the walls of said sections. 70

7. A duplex casing for wells, conduits, or drainage purposes, comprising telescoping sections, each section having spiral corrugations extending longitudinally and adapted to engage the corrugations of the telescoping section, the intermediate portions between the corrugations of the outer section being spaced from the corresponding part of the inner section, whereby a spirally extending cavity or space is provided between the walls of said sections, each of said intermediate portions being provided with perforations or slots. 80

8. A duplex casing for wells, conduits, or drainage purposes, comprising telescoping sections, each section having spiral corrugations extending longitudinally and adapted to engage the corrugations of the telescoping section, the intermediate portions between the corrugations of the outer section being spaced from the corresponding part of the inner section, whereby a spirally extending cavity or space is provided between the walls of said sections, each of said intermediate portions being provided with perforations or slots, the adjacent slots in the inner and outer walls being arranged at different angles. 90

9. A duplex casing for wells, conduits, or drainage purposes, comprising telescoping sections, each section having spiral corrugations extending longitudinally and adapted to engage the corrugations of the telescoping section, said outer and said inner sections having in the intermediate portions between said corrugations, smooth-walled 100 slots providing channels through the duplex walls of the casing. 105

10. A duplex casing for wells, conduits, or drainage purposes, comprising telescoping sections, each section being spirally corrugated throughout its entire length and adapted to thread the corrugations of the telescoping section, the joints between abutting outer sections and the joints between abutting inner sections alternating 115 with each other, so that the intermediate portions of each outer section and each inner section reinforce the joint intermediate of its ends. 120

11. A duplex casing for wells, conduits, or drainage purposes, comprising telescoping sections, each section having spiral corrugations extending longitudinally and adapted to engage the corrugations of the telescoping section, the intermediate por- 130

tions between the corrugations of the outer section being spaced from the corresponding part of the inner section, whereby a spirally extending cavity or space is provided between the walls of said sections, the intermediate portions of the outer sections being provided with perforations or slots.

12. A sheet metal casing comprising inner and outer telescoping sections, each section having spiral corrugations extending longitudinally and adapted to engage the corrugations of the telescoping section, the inner sections tapering from the center in opposite directions, and the outer sections flaring from the center in opposite directions. 15

In testimony whereof I affix my signature in presence of two witnesses.

ANDREW SMITH.
